UNITED STATES PATENT OFFICE.

ALEXANDER SEBESTYEN, OF NEW YORK, N. Y.

TOY.

1,164,411.

Specification of Letters Patent. Patented Dec. 14, 1915.

Application filed December 21, 1914. Serial No. 878,361.

To all whom it may concern:

Be it known that I, ALEXANDER SEBESTYEN, a subject of the Emperor of Austria-Hungary, residing at New York, in the county of New York and State of New York, have 5 invented certain new and useful Improvements in Toys; and I do hereby declare the following to be a full, clear, and exact description of the invention, such as will enable others skilled in the art to which it 10 appertains to make and use the same.

This invention relates to new and useful improvements in toys and has for its principal object to provide a toy which will be 15 particularly interesting to children and which will instruct them particularly as to the method in which iron is worked.

Another object of the invention is to provide a moving toy which may be easily operated by a sliding plunger and which can be easily and cheaply constructed of wood or any other suitable material.

With these and other objects in view, the 20 invention consists in the novel combination and arrangement of parts which will be fully set forth in the following specification and accompanying drawings, in which,

Figure 1 is a longitudinal sectional view 25 of a toy constructed in accordance with this invention showing a portion thereof in elevation, and, Fig. 2 is a transverse sectional view taken on line 2—2 of Fig. 1.

Referring now to the drawings by characters of reference, the numeral 1 designates 30 a base of the device which is provided a longitudinal groove 2. This groove forms a guide for the sliding actuating rod 3 which is provided on its upper surface with a pair of screw eyes 4 the use of which will appear 35 as the description proceeds. Supported centrally of the longitudinal extremities of the base 1 is the anvil base block 5 which is designed to support the member 6 which is 40 shaped to represent an anvil. The element 7 is designed to represent the metal which 45 rests upon the anvil and may be painted or colored in any suitable manner to represent a piece of hot metal upon which the hammers of the figures which will be more fully 50 hereinafter described strike.

Secured to the base 1 near each end are the figures designated generally by the numeral 8 which comprises the legs 9 which are secured in such a position that they 55 straddle the groove 2. Pivotal secured as at 10 to the legs 9 is the body 11 which is

provided with a suitable screw eye 12 to which the flexible connection 13 is secured. This flexible connection is also connected to the screw eyes 4 and it will thus be seen 60 that a connection is formed between the body 11 and the actuating rod 3. The arms 14 of the body are so arranged that they support between their free ends the hammer handle 15 which carries the head 16, 65 which head is designed to engage the element 7 when the device is actuated.

It will be apparent from the foregoing 70 that in use the actuating rod 3 is slid longitudinally through the groove 2 and this action will cause the flexible connection 13 to exert pull on the eyelets thereby swinging the bodies 11 on their pivot pin and causing the figures to swing the hammers downwardly and into engagement with the element 7 thus representing iron workers striking 75 the element 7 and thereby instructing and amusing those watching the operation of the device.

While in the foregoing there has been 80 shown and described the preferred embodiment of this invention, it is to be understood that such changes may be made in the combination and arrangement of parts as will fall within the spirit and scope of the 85 appended claims.

What is claimed is:—

1. A toy of the character described comprising a base having a groove therein, articulated figures secured to the upper surface of the base straddling the groove, an anvil supported intermediate the ends of the base, hammers carried by the figures and means 90 slidable in the grooves to cause the figures to move and thereby bring the 95 hammers into contact with the anvil.

2. A toy of the character described comprising a base having a longitudinal groove extending throughout its entire length, figures secured to the base and straddling the 100 groove, said figures being jointed, an anvil supported on the base intermediate its ends, hammers carried by the figures and adapted to engage the anvil, a bar slidable in the groove and a flexible connection between 105 each of the figures and the bar whereby when the bar is reciprocated, the figures will move and thereby represent metal workers using an anvil.

3. A toy of the character described comprising a base having a longitudinal groove extending throughout its entire length, a 110

bar slideable in the groove, a handle portion on the bar, an anvil supported on the base intermediate its ends, figures secured to each end of the base, said figures straddling the groove and being jointed, hammers carried by the figures and designed to engage the anvil and flexible connections secured to the figures and to the bar whereby when the bar is reciprocated the figures will move and

bring the hammers into engagement with the anvil.

In testimony whereof I affix my signature in presence of two witnesses.

ALEXANDER SEBESTYEN.
